CHAIR

Gordon W. Florian, Fairfield, Harry W. Streck,
Bridgeport, and William E. Kelsey, Jr., Fair-
field, Conn.

Application April 15, 1952, Serial No. 19,337

Term of patent 3½ years

(Cl. D15—8)

To all whom it may concern:

Be it known that we, Gordon W. Florian, Harry W. Streck, and William E. Kelsey, Jr., citizens of the United States and residents, respectively, of Fairfield, Bridgeport, and Fairfield, all in the county of Fairfield and State of Connecticut, have invented a new, original, and ornamental Design for a Chair, of which the following is a specification, reference being had to the accompanying drawings, forming part thereof.

In the drawings:

Fig. 1 is a front elevation of a chair, showing our new design;

Fig. 2 is a side elevation;

Fig. 3 is a rear elevation;

Fig. 4 is a top plan view; and

Fig. 5 is a bottom plan view.

We claim:

The ornamental design for a chair, substantially as shown.

GORDON W. FLORIAN.
HARRY W. STRECK.
WILLIAM E. KELSEY, JR.
